UNITED STATES PATENT OFFICE.

EUGENE PREATOR, OF BURLINGTON, WYOMING.

WIRE-STRETCHING MACHINE.

1,142,908.

Specification of Letters Patent. Patented June 15, 1915.

Application filed August 8, 1914. Serial No. 855,778.

To all whom it may concern:

Be it known that I, EUGENE PREATOR, a citizen of the United States, residing at Burlington, in the county of Bighorn and 5 State of Wyoming, have invented a new and useful Wire-Stretching Machine; and I do hereby declare the following to be a full, clear, and exact description of the invention, such as will enable others skilled in the art 10 to which it appertains to make and use the same.

This invention relates to an improved wire stretching machine, and an object of the invention is to provide a machine of this nature comprising essential, efficient and practical features of construction.

One of the features of construction is the provision of a bar having curved forks at one end provided with oppositely disposed 20 plates connecting said forks, there being a sprocket between said plates with which a sprocket chain engages, the curved forks acting to guard and hold the chain upon the sprocket, there being a toothed wheel and 25 dog adjacent one of said plates to hold the sprocket in adjusted positions as well as holding the chain also in adjusted positions, or taut.

In practical fields the details of construction may be subjected to alterations, falling 30 within the scope of what is claimed.

The invention comprises further features and combination of parts, as hereinafter set forth, shown in the drawings and claimed.

35 In the drawings:—Figure 1 is a plan view showing one application of the stretcher. Fig. 2 is an enlarged view in elevation and partly in section, showing the detail features of the stretching mechanism. Fig. 3 is an 40 enlarged sectional view upon an angular line 3—3 of Fig. 2 looking in two directions, as indicated by the arrows *a* and *b*. Fig. 4 is a view in side elevation, showing a modified form of ratchet and sprocket mechanism 45 for manipulating the chain 23, for stretching a wire which is gripped or clamped in one of the grippers or clamps 25. Fig. 5 is an enlarged view in side elevation of the form of construction shown in Fig. 4. Fig. 50 6 is a plan view of the modified ratchet and sprocket mechanism shown in Fig. 4, and illustrating one of the clamps 25 as having been inserted through a ring so that the chain 23 will engage the ring, whereby a

wire meshwork may be stretched. Fig. 7 55 is a sectional view on line 9—9 of Fig. 4.

Referring more especially to the drawings, 1 designates a bar, which may be of any desired length and construction. However, this bar terminates at one end in an eye 60 3 and a hook 4. The other end of the bar terminates in curved forks 5. Riveted to the forks upon the opposite faces are oppositely disposed plates 6, and mounted in bearings of said plates is a short shaft 7 65 having a sprocket wheel 8, which is arranged between said plates. Also riveted at 6^a to the face of one of the plates 6 at one end thereof is an L-shaped plate. 7^a, as shown clearly in Figs. 1, 2 and 3. The short shaft 70 7 has one end mounted in said L-shaped plate, as shown clearly in Fig. 3. A lever 12^a having a crank handle 12^b is provided, and has its forked end 12^c loosely pivoted or mounted upon the short shaft 7. Between 75 the forks of said lever 12^a is a toothed wheel 9, which is keyed at 14^a to the shaft 7. The lever 12^a adjacent the crotch between the forks of said lever is provided with a pocket 12^d, in which a dog or pin 18 is mounted. 80 This dog or pin 18 is cylindrical in contour and is provided with a contracted shank 18^b extending through a bore 18^c and provided with a head 18^d. The lever 12^a is provided with a transverse opening 12^e, in which the 85 head 18^d is located. A spring 15^a surrounds the shank 18^b and is interposed between the pin 18 and one end of the pocket 12^d, and acting to hold the pin 18 in engagement with the toothed wheel 9. 90

The L-shaped plate 6^a is provided with a pocket 6^e, in which a dog or pin 6^g similar to the pin 18 is mounted. The attending parts of the pin 6^g are identical with those of the pin 18. However, when the lever 12^a is 95 moved downwardly in the direction of the arrow *e*, the pin 18 will slip over or by the teeth of the wheel 9, in order to gain the hold or contact with another tooth of the wheel 9. In moving the lever 12^a downwardly in this manner so that the pin 18 will engage another tooth, the pin 6^g will act to prevent retrogression of the wheel 9. When moving the lever 12^a in a direction reverse to that indicated by the arrow *e*, that is, after permitting the pin or dog 18 to engage another tooth, the wheel 9 is given a partial 100 rotation causing the shaft 7 to correspond-

ingly rotate and with it the sprocket 8, which will operate the chain 23. When rotating the wheel 9 in this manner the pin 6^g rides or slips over the teeth thereof. The slipping of the pins or dogs 6^g and 18 over said teeth is allowed, owing to said dog being beveled off as shown at 24^a. A quick movement of the lever 12^a as it imparts an intermittent motion to the toothed wheel and shaft 7 and in turn to the sprocket 8, and by adjusting the pins or dogs 6^g and 18, so that said bevels will face just the opposite to that shown in Fig. 2, an intermittent motion may be imparted to the toothed wheel, the shaft 7, and the sprocket 8 in a reverse direction. When the chain 23 is secured around a post and one of the clamps 25 clamping said chain 23 and a wire to be stretched clamped in another clamp 25, as shown clearly in Fig. 1, and the lever 12^a manipulated, the wire may be stretched. A wire may be stretched in another manner, by placing the chain 27 in engagement with a post as shown in Fig. 4 (which shows a modified form of crank-ing, ratchet and sprocket mechanism for operating the chain 23), and the wire clamped or gripped in one of the clamps 25 of the chain 23, and by turning the crank 12 or lever, motion may be imparted to the chain 23 for stretching the wire. The form and construction shown in Fig. 1 may be used and applied in the manner similar to that shown in Fig. 4, or in a manner similar to that shown in Fig. 6. In Figs. 4 and 5 the form of lever 12^a is dispensed with, and a crank handle 12 substituted, which crank handle is provided with rectangular openings 11 to engage the rectangular extension 10 of the shaft 7, on which the sprocket 8 and the toothed wheel 9 may be keyed (not shown), and when using the crank handle 12 only one dog or pin 18^h (which is similar to the pins 16^g and 18) is used. The dog or pin 18^h comprises an enlarged cylindrical portion at its lower end, and a contracted cylindrical extension at the other end portion. The contracted cylindrical portion 18^k engages the contracted portion 50 of the bore 17, while the enlarged cylindrical portion 19 engages the larger portion of the bore 17, there being a coil spring interposed between the shoulder 20 of the dog or pin and the shoulder 21 of said bore, acting to hold the dog in engagement with any one of the notches of the toothed wheel, so as to hold the sprocket in adjusted positions, which in turn holds the sprocket chain 23 taut. The lower end of the enlarged portion 60 of said dog is beveled as shown at 24, and owing to the pin or dog being cylindrical, it will be observed that the dog may be rotated partially, so that the beveled portion may be disposed in such wise that the toothed wheel may slip by the dog in one direction

or the other. For instance, if one of the clamps 25 of the sprocket chain 23 is connected to one wire, and the sprocket chain pulls to stretch said wire, the dog will slip by the teeth of the toothed wheel, which is being rotated in one direction. The clamp of the other end of the sprocket chain, which is then longer than the first portion, is placed in engagement with another wire to be stretched. In this case the dog or pin 70 must be partially rotated, so that the beveled portion thereof will permit the toothed wheel to slip by, the same moving in a direction just the opposite to the direction in the first instance. A chain 27 is connected 75 to the eye 3, and the other end of this chain is connected to a clamp 25. Both ends of the sprocket chain are provided with clamps 25. Each clamp comprises a body portion 28 having an eye 29 at one end to which a chain 80 is connected, while the other end portion of the body is in the form of a flat plate having an elongated slot 31 and provided with laterally extending flanges 32 and 33. The flange 32 is in a position parallel to the slot, 85 while the flange 33 is arranged at an angle to the slot. Arranged in the slot is a roller bearing 34 having an annular groove 35, which is engaged by the opposite edges of the slot. This groove is formed, owing to 90 one of the end portions 36 of the roller bearing being shrunk upon the roller bearing. In clamping a wire, the same is placed between the threaded portion of the roller bearing and the lateral flange which extends 95 at an angle to the slot, and the roller bearing so adjusted as to frictionally engage the wire, as shown in the drawing.

In using the machine or device in the manner shown in Fig. 1, the sprocket chain 100 is passed about a post or the like, and the clamp is arranged so that the body of the sprocket chain engages between the roller bearing and the flange which extends at an angle to the slot, then the clamp at the end 105 of the other chain is placed in engagement with the wire, subsequently to which the shaft is rotated by the lever 12^a.

In using the device or machine in the manner as illustrated in Fig. 4, the chain 110 27 is fastened about a post or the like, and one of the links of said chain arranged in engagement with the hook of said bar, and one of the clamps at one end or the other 115 of the sprocket chain is placed in engagement with a wire to be stretched, subsequently to the shaft which is rotated by the crank handle.

In using the device or machine in the manner as illustrated in Fig. 6, the sprocket 120 chain is arranged in an eye of the clamping frame 38, which in turn clamps a wire netting, subsequently to which the shaft is rotated by the crank handle.

Any suitable chains may be used in con-

junction with this machine, therefore it is to be understood that the patentee is not limited to any particular form of chain.

The invention having been set forth, what is claimed as new and useful is:—

1. In a device as set forth, a frame comprising a bar having a hook at one end, and curved forks at the other end, a connection between the hook including a clamp and a wire to be stretched, a pair of plates fixed upon opposite faces of the curved forks, a sprocket wheel mounted between said plates, a shaft mounted in the plates and on which shaft the sprocket wheel is keyed, a cranking member on one end of the shaft, a toothed wheel keyed to the other end of the shaft, means to coöperate with the toothed wheel so that it may be rotated in one direction or the other and prevented from rotation in an opposite direction and vice versa, and connections between the sprocket wheel and an anchoring member.

2. In a device as set forth, a frame comprising a bar having an eye at one end, and curved forks at the other end, a connection between the eye including a clamp and the wire to be stretched, a pair of plates fixed

upon opposite faces of said forks, a sprocket wheel mounted between said plates, a shaft mounted in the plates and on which shaft the sprocket wheel is keyed, an L-shaped plate mounted upon one face of one of the plates, and having a bearing in which one end of said shaft is mounted, a lever loosely mounted upon the shaft between the L-shaped plate and the adjacent plate, said lever having a forked end which is loosely mounted on the shaft, a toothed wheel on the shaft between the forks, reversible means carried by the lever to engage the toothed wheel, whereby an intermittent motion may be imparted to the toothed wheel and shaft in one direction or the other, and reversible means carried by the L-shaped plate to prevent retrogression of the toothed wheel, and connections between the sprocket wheel and an anchoring member.

In testimony whereof I have signed my name to this specification in the presence of two subscribing witnesses.

EUGENE PREATOR.
